UNITED STATES PATENT OFFICE.

WILLIAM S. EASTON, OF PORTLAND, OREGON, ASSIGNOR TO UTILITY MANUFACTURING COMPANY, OF SEATTLE, WASHINGTON, A CORPORATION OF WASHINGTON.

WATER-MOTOR.

1,115,655.

Specification of Letters Patent.

Patented Nov. 3, 1914.

Application filed December 6, 1913. Serial No. 805,094.

To all whom it may concern:

Be it known that I, WILLIAM S. EASTON, a citizen of the United States, residing at Portland, in the county of Multnomah and State of Oregon, have invented new and useful Improvements in Water-Motors, of which the following is a specification.

The invention relates to motors, and more particularly to the class of water power motors.

The primary object of the invention is the provision of a motor wherein the same can be entirely submerged in a body of water without affecting the perfect operation thereof, or it can be partly submerged, the paddle wheels being of novel form so that the full power of the water can be utilized for driving machinery or the like.

Another object of the invention is the provision of a water motor which is simple in construction, reliable and efficient in operation, and inexpensive in manufacture.

With these and other objects in view, the invention consists in the construction, combination and arrangement of parts as will be hereinafter fully described, illustrated in the accompanying drawing, and pointed out in the claim hereunto appended.

In the drawings:—Figure 1 is a side elevation of a motor constructed in accordance with the invention. Fig. 2 is a vertical longitudinal sectional view therethrough. Fig. 3 is a transverse sectional view through the motor. Fig. 4 is a similar view on the line 4—4 of Fig. 1.

Similar reference characters indicate corresponding parts throughout the several views in the drawings.

Referring to the drawings in detail, the motor comprises a casing A having a solid flat top 5, bottom 6, sides 7, and upper ends 8, below which are formed the gateways 9 for the passage of the water through the casing A, one of the end walls 8 being inwardly inclined and is designed to direct the current of water in which the casing A is arranged into the gateway beneath the said wall so that it will flow through the casing for operating paddle wheels presently described.

Arranged medially within the casing A and extending from the top downwardly is a partition or baffle plate 10 which is inclined

correspondingly to the inclined end wall 8 and serves to prevent the splashing of the water when acted upon by one of the paddle wheels over the uppermost point of the other paddle wheel.

At each side of the baffle plate 10 and extending transversely through the casing A are horizontal shafts 11 to which are fixed the wheel-like ends 12 of the paddle wheel, and at diametrically opposite points in these ends 12 are fixed journals or pintle rods 13, the same being also passed through eye members 14 which are fixed to paddle blades 15, the eye members 14 on each paddle blade 15 being mounted near one longitudinal edge thereof, and each blade 15 is of a width so that its free longitudinal edge will contact with the shaft 11 when in a position to receive the impact of the water current so that the paddle wheel will be rotated. When the paddle wheels are rotated, and each blade thereof is rising out of the water, the same is free to feather the water so as not to interfere with the rotation of the paddle wheels when one or two of the blades are submerged in the body of water passing through the casing A, thereby assuring the complete rotation of the paddle wheels for the driving of the shafts 11.

Mounted on the ends of the shafts 11 projected beyond one side of the casing exteriorly thereof are beveled gears 16, the same meshing with beveled pinions 17 fixed to a counter shaft 18 journaled in bearings 19 suitably secured to the casing A exteriorly thereof. Loosely journaled upon this counter shaft 18 is a pulley wheel 20 over which is trained a driving cable or belt 21 which when driven will impart power to machinery or the like, the hub of the pulley 20 being formed with a clutch 22 with which is engaged a companion clutch 23 slidably keyed to the shaft 18 and having connected thereto a throw lever 24 which is pivoted at 25 to the casing so that on operating the lever in one direction the pulley wheel 20 can be locked upon the shaft 18, and on operating the lever in the reverse direction said pulley 20 will be free on the shaft for the stopping and starting of the machinery or the like driven by the water motor.

From the foregoing it is thought that the construction and manner of operation of the

device will be clearly understood, and therefore a more extended explanation has been omitted.

What is claimed is:—

- 5 A water motor comprising a substantially rectangular casing, spaced parallel shafts journaled transversely in the casing, wheels fixed on the ends of said shafts, pintle rods mounted at diametrically opposite points in the wheel, paddle blades swingingly connected to the pintle rods and having their free ends normally contacting said shafts, the end walls of said casing terminating approximately in a plane with the transverse
- 10

axis of said shaft, one of said end walls being inclined inwardly to direct the water below said shaft on entrance into the casing, and a baffle blade arranged within the casing between said shafts and correspondingly inclined with respect to said inclined wall to 15 maintain the water at a constant level in its passage through the casing.

In testimony whereof I affix my signature in presence of two witnesses.

WILLIAM S. EASTON.
